HEATER FOR FURNACES AND METHOD OF
OPERATING THE SAMEArthur H. Vaughan, Salem, Ohio, assignor to
The Electric Furnace Company, Salem, Ohio,
a corporation of Ohio

Application October 26, 1935, Serial No. 46,911

5 Claims. (Cl. 126—91)

This invention relates generally to heat treating furnaces, and more particularly to heaters for such furnaces and to a method of operating such heaters.

5 Heat treating furnaces are often supplied with a protective atmosphere for preventing oxidation of the work during its heating and cooling. Many of such furnaces containing a protective atmosphere in contact with the work being heated 10 are heated by electrical resistors, since the use of fuel fired furnaces in which the products of combustion come into contact with the work would lead to oxidation of the work. There are many cases, however, where it is advisable from 15 an economic standpoint to employ a combustible fuel rather than electricity for heating the furnace. It has been proposed heretofore to provide the heating chamber of the furnace with a double surface heat exchanger, usually in the 20 form of a combustion tube, and to burn a mixture of fuel such as gas, and air within the heat exchanger in order to heat the furnace. The present invention relates to this type of furnace in which the heating is accomplished by the 25 combustion of fuel in a double surface heat exchanger or combustion tube.

In the accompanying drawings which illustrate by way of example two embodiments of my invention,

30 Figure 1 is a front elevation, parts being shown in section, of a heat treating furnace comprising a heating chamber and a cooling chamber and embodying my improved means for heating the heating chamber;

35 Figure 2 is a transverse vertical section taken on the line II—II of Figure 1;

Figure 3 is a partial transverse vertical section taken in the same plane as that shown in Figure 2, but illustrating the double surface heat ex- 40 changer on an enlarged scale; and

45 Figure 4 is a partial horizontal longitudinal section through the furnace showing a modified form of the invention in which the heat exchanger is U-shaped and has both its inlet and outlet ends extending through the same wall of the furnace.

It has been proposed heretofore to supply an 50 intimate mixture of fuel and air to one end of a combustion tube placed within a furnace and to cause the products of combustion to traverse the tube. In such cases, particularly where the combustion tube is of considerable length, it is difficult, if not impossible, to liberate the heat 55 of combustion uniformly throughout the length of the tube, and this results in uneven heating

of portions of the furnace chamber. It has been proposed also to introduce at one end of the combustion tube concentric parallel flowing streams of fuel and air which mix during their flow through the combustion tube and burn to liberate heat. In this method, burners of the diffusion type are employed producing a long slow burning flame, the fuel and air passing through the tube at a low velocity. The fuel and air mix slowly and therefore burn slowly; 10 but there is no positive control of the combustion reaction which takes place within the tube. Accordingly, it is difficult, if not impossible, to produce uniform liberation of heat by the combustion process if uniform distribution of heat is 15 desired, or to regulate the distribution of heat in different parts of the tube where that is desired. As a result, certain parts of the tube heat to a greater extent than other parts and, 20 accordingly, deteriorate more rapidly.

My invention enables me to cause liberation of heat throughout the entire length of the tube if that be desired, or to control the liberation of heat along the length of the tube so as to produce either uniform heat liberation or a local 25 excess of heat, as may be desired. Generally speaking, this is accomplished by introducing fuel such as gas, mixed with a deficiency of air into the interior of a double surface heat exchanger or combustion tube. The products of partial 30 combustion flow longitudinally through the tube, and as they flow, are supplied with additional quantities of air introduced into the heat exchanger by means of a secondary air pipe or other suitable means. The secondary air so admitted augments the air originally present in the mixture and enables substantially complete 35 combustion of the fuel to take place. The secondary air is admitted at predetermined points and in predetermined amounts to the fuel and 40 partial products of combustion as they flow along the tube. This produces a gradual increase in the burning of the mixture throughout the length of the tube. It provides for positive control of the points at which the secondary air is admitted 45 and for the amount of secondary air. The process of combustion can therefore be accurately controlled so as to liberate heat where desired, in contradistinction with the method wherein a diffusion type burner is employed and in which 50 the control of the burning process ceases upon the introduction of the fuel and air into the combustion tube.

Referring more particularly to the accompanying 55 drawings, in which the invention is illustrated

in connection with a heat treating furnace, there is shown a furnace indicated generally by the reference numeral 2 and comprising a heating section 3 and a cooling section 4. The heat treating furnace is of conventional type, the heating section 3 having a shell 5, an inner refractory lining 6, and an intermediate lining 7 of thermal insulation. The cooling section 4 is provided with a water cooled jacket 8. The work to be heat treated is passed through the heating and cooling sections by a plurality of chain conveyors 10 which pass around driven sprockets 11 adjacent the exit end of the cooling section and around idler sprockets 12 adjacent the entrance end of the heating section of the furnace. Non-oxidizing gas is introduced into the heating chamber through a pipe 13 provided with a valve 13a.

Located inside of the furnace chamber 14 are a plurality of double surface heat exchangers or combustion tubes 15, which will be referred to hereinafter for purposes of conciseness as combustion tubes. Each of these tubes is supported by a strap 16 and a hanger rod 17 extending through the roof of the furnace. Each of the combustion tubes comprises a main body portion 18 having a length slightly greater than the width of the furnace chamber. An inlet pipe 19 is connected to one end of the tube 15. The other end 20 of the inlet pipe 19 extends into a chamber 21 formed by a casting 22 provided with a cover 23. The connection between the inlet pipe and casting 22 is sealed by a gland 24 and packing 25, the gland being adjustable by means of a screw 26. The gland 24 is provided with openings 27 so that a mixture of fuel and air supplied through the pipe 28 can enter the inlet pipe 19 and thus pass into the combustion tube.

The tube 15 is provided at its left-hand end as viewed in Figure 2, with an enlarged portion 30 which receives a helical heat absorber 31 best shown in Figure 3. The combustion tube is held firmly in place in the opening 32 by providing a bead 33 on the portion 30, which bead seats against a ring seat 34 and is held in place by a ring clamp 35. An elbow 36 connected to the end of the tube section 30 acts as a chimney for the products of combustion escaping from the combustion tube.

50 A secondary air tube 37 located inside of the combustion tube 15 is in communication at its outer end 38 with the interior of the heat absorber 31. The secondary air tube is closed at its inner end 39 and is provided along its length with orifices 40 for supplying secondary air to the space 41 between the tubes 37 and 15. The tube 37 is provided with feet 42 for spacing it from the combustion tube. Secondary air is supplied to the interior of the heat absorber through pipe 43.

60 The products of combustion, before passing out of the chimney 36, flow along the helical passage 44 between the outer surface of the heat absorber 31 and the inner surface of the enlarged portion 30. The interior of the heat absorber is provided with a core 45 closed at its ends and which forms with the walls of the absorber 31, a helical passage 46 for the secondary air supplied through pipe 43. In this manner, heat from the products of combustion is transferred to the incoming secondary air as it passes through the heat absorber, and this heated air is thereafter delivered through the orifices 40 into the space 41 for combining with any unburned portions of the mixture of air and fuel.

65 Any suitable arrangement may be employed for

supplying a mixture of fuel and air to the combustion tube 15 and for supplying secondary air to the secondary air tube. One suitable means is illustrated in Figure 2. Air under pressure is supplied through a pipe 50 provided with a valve 51. The air passes through a metering orifice 52 to an inspirator 53, to which is connected a gas pipe 54. The mixture of gas and air flows from the inspirator through pipe 55 and branch pipes 56, each of which delivers the mixture to the 10 chamber 21 associated with one of the combustion tubes. The secondary air admitted into the combustion tube through pipe 43 is supplied through pipes 57, 58 and 59. A portion of the air admitted into pipe 50 flows through a metering orifice 60 and a three-way valve 61 to the pipe 58. A by-pass pipe 62 is connected at one end to the valve 61 and at the other by a T 63 to the pipe 55. Air normally flows through the pipe 62 only during the starting of the furnace, 20 as hereinafter described.

In operating the furnace, the inspirator 53 is adjusted to deliver a very rich mixture of gas and air, usually containing about 50% of the air required for perfect combustion. During normal 25 operation of the furnace, this rich mixture enters the combustion tube 15 through inlet pipes 19 and burns inside the tube with liberation of a part of the potential heat of the gas. Generally, I use a mixture as rich as can be burned in the presence 30 of heat without depositing carbon. The products of partial combustion still contain relatively great fuel value and this is utilized by causing further combustion to take place with liberation of additional heat by supplying air through the 35 secondary air tubes 37 from which it issues through the orifices 40 and mixes with the partially burned gases flowing along the combustion tube. The waste gases, after being subjected to approximately complete combustion, escape 40 through the end portion 30 of the combustion tube and the chimney 36. The air entering the secondary air tube is considerably heated by conduction through the walls of the secondary air tube and through the walls of the heat absorber 45 31. This results in the recovery and re-use of heat from the waste products and thus reduces the amount of fuel needed under given conditions.

For lighting up a cold furnace, special procedure is necessary as the rich mixture previously 50 referred to will not usually burn except in heated surroundings. Accordingly, I place the three-way valve 61 in position to cause the air passing through the orifice 60 in the upper portion of pipe 57 to re-join the main stream at the T 63, thus 55 providing a mixture in about the proportions for perfect combustion. The valve 61 is then adjusted to give a relatively small flow and the mixture is ignited at the opening of the chimney 36. The flame burns back into the combustion tube 60 and finally reaches the discharge opening 65 of the inlet pipe 19. This pipe is proportioned so as to give a sufficiently high velocity of mixture to prevent the flame striking back into the header 22. The mixture is now allowed to burn for a 65 time sufficient to heat up the tube to a high enough temperature to maintain combustion of the normal rich mixture. Then the position of valve 61 is reversed so as to cause the air flowing through orifice 60 to be delivered to the secondary air 70 pipe 37 through pipes 58, 59 and 43.

In Figure 4 there is shown a modified form of the invention in which a U-shaped combustion tube is employed having both legs extending through openings in the same furnace wall. In 75

this embodiment, a fuel-rich mixture of gas and air is introduced through pipe 70 and flows through a fitting 71 located in the left-hand end of the leg 72 of the combustion tube indicated 5 generally by the reference numeral 73. A secondary air tube 74 extends through the fitting 71 and into the leg 72. The mixture of gas and primary air flowing through the fitting 71 passes through an orifice 75 formed between the fitting 10 and an enlargement 76 on the secondary air tube 74. After the mixture of gas and air has passed into the leg 72, it is supplied with secondary air issuing through orifices 77. Another secondary air tube 78 provided with orifices 79 is arranged 15 in the leg 80 of the combustion tube. The tube 78 provides additional air for completing the burning of any unburned portions of gas passing into the leg 80. The products of substantially complete combustion pass the heat absorber 81, 20 which is identical in construction with the heat absorber 31 shown in Figure 3, and escape through the chimney 82. The secondary air supplied to the tube 78 is heated by passing through the heat absorber before it is delivered from the orifices 25 79, as previously described.

While I have shown and described certain means for supplying the combustion tubes with a mixture of fuel and air and for introducing secondary air, any other suitable arrangement may 30 be employed. The distribution of air orifices in the secondary air tubes may be made to suit particular requirements, depending upon the characteristics of the fuel used and upon the distribution of heat input desired. Even without physical 35 changes in the apparatus, I have found it possible to adjust the rates and distribution of heat input through a considerable range over the length of the tube by adjusting the amount and ratio of gas-air mixture and the amount of secondary air admitted. The invention provides for the positive 40 control of the process of combustion in the combustion tubes so that heat may be liberated as and where desired.

I have illustrated and described two embodiments of my invention, but it will be understood 45 that the invention may be otherwise embodied or practiced within the scope of the following claims.

I claim:

1. Heating means for furnaces comprising a tube type heat exchanger having an inlet in communication with fuel and air supplies and an outlet for the discharge of products of combustion, a secondary air tube extending through the outlet of the heat exchanger for supplying secondary air to the space between it and the heat exchanger, and means in the outlet of the heat exchanger for transferring heat from the products of combustion to the incoming secondary air.
2. In a heat treating furnace, walls enclosing a heating chamber, a combustion tube traversing said heating chamber, a portion of the combustion tube within the heating chamber being imperforate, conduits communicating with the interior of said combustion tube at opposite ends thereof and extending exteriorly of said walls, means for introducing fuel with a predetermined amount of primary air insufficient for complete combustion through one of said conduits and flowing products of partial combustion toward

the opposite end of the combustion tube, a secondary air tube extending through the other of said conduits, the secondary air tube extending through the major portion of the effective length of the combustion tube and being provided with 5 perforations throughout substantially all of its length within the effective portion of the combustion tube, means for supplying through said secondary air tube predetermined amounts of secondary air for progressive further combustion 10 of said products while so traveling, and means for varying the amounts of fuel, primary air and secondary air in substantially constant ratio to each other.

3. Heating means for the chamber of a heat 15 treating furnace, comprising a combustion tube having its interior sealed from the atmosphere of the furnace chamber, means for introducing a mixture of fuel and a deficiency of air to said combustion tube adjacent one end thereof, for 20 partial combustion adjacent said end and for causing the products of partial combustion to flow toward the opposite end of the combustion tube, means for equalizing temperature 25 throughout substantially the length of the combustion tube comprising a secondary air tube extending into the combustion tube through said opposite end, the secondary air tube extending through the major portion of the effective length 30 of the combustion tube and being provided with perforations throughout substantially all of its length within the effective portion of the combustion tube, and means for supplying a predetermined amount of additional air from outside 35 the furnace through said secondary air tube for progressive further combustion of said products while so traveling, whereby the secondary air is supplied to the combustion tube in a direction counter-current to the flow of products of combustion.

4. The process of burning a fuel which comprises intimately mixing the fuel with an amount of primary air insufficient for complete combustion, introducing the mixture into an elongated combustion zone adjacent one end thereof, flowing the products of partial combustion toward the opposite end of the combustion zone and supplying secondary air to the combustion zone in a direction counter-current to the flow of the products of partial combustion and along the 50 major length of the combustion zone for the progressive further combustion of said products while maintaining the combustion zone out of communication with the atmosphere outside it.

5. The process of burning a fuel which comprises intimately mixing the fuel with primary air in an amount approximately 50% of that required for perfect combustion, introducing the mixture into an elongated combustion zone adjacent one end thereof, flowing the products of 55 partial combustion toward the opposite end of the combustion zone and supplying secondary air to the combustion zone in a direction counter-current to the flow of the products of partial combustion and along the major length of the 60 combustion zone for the progressive further combustion of said products while maintaining the combustion zone out of communication with the atmosphere outside it.
